UNITED STATES PATENT OFFICE.

WALTER RELLAND LAINE, OF LOS ANGELES, CALIFORNIA, ASSIGNOR OF ONE-THIRD
TO ALEXANDER ROBB MERRIMAN, OF LOS ANGELES, CALIFORNIA.

ROTARY NEGATIVE-DEVELOPING MACHINE FOR PHOTOGRAPHERS.

1,113,564.

Specification of Letters Patent.

Patented Oct. 6, 1914.

Application filed March 31, 1913. Serial No. 758,059.

To all whom it may concern:

Be it known that I, WALTER RELLAND LAINE, a citizen of the United States, residing in the city of Los Angeles, State of California, have invented a new and useful ⁵ Rotary Negative-Developing Machine for Photographers, of which the following is a specification.

One of the objects of this invention is to provide ¹⁰ a mechanical device that will agitate the developing solution, wherein the plates are immersed, in an effective manner, so as to produce an even development of all parts of the picture; to economize time by dispensing to ¹⁵ a great extent with the work of skilled photographers; to provide more sanitary means for developing the plates; and to develop the plates more economically by reason of saving in the cost of the developing solution, ²⁰ and in the length of time required for the developing solution to do its work.

The invention pertains to a specially constructed tank adapted to hold the photographic plates safely in place, within the developing solution, and further includes an arrangement for withdrawing one rotary tank from the means for rotating the same, and substituting a larger or smaller tank in its place so as to adapt a device for handling photographic plates differing greatly ²⁵ in size.

Various other objects and advantages will hereinafter appear.

The invention consists in the various ³⁵ parts, combinations of parts, and details of construction, all of which will be described in connection with the accompanying drawings, and then definitely pointed out in claims, some of which will cover the invention broadly, and others will be directed ⁴⁰ more to details and specific improvements.

Referring to the accompanying drawings which illustrate the invention, Figure 1 is a side elevation of the complete machine, the ⁴⁵ same being shown using a rather large developing tank. Fig. 2 is an end elevation looking at the right end of Fig. 1. Fig. 3 is a top plan view of Fig. 1. Fig. 4 is a side view of the tank, partly in section and ⁵⁰ partly in elevation. Fig. 5 is a perspective view of one form of plate holding device which may be inserted within the tank. Fig. 6 is a detail view of a portion of the means to removably support the developing tank ⁵⁵ for rotation. Fig. 7 is a perspective view

of the preferred form of plate holding device. Fig. 8 is an enlarged, broken, transverse section of one of the guiding members of the plate holding device. Fig. 9 is a cross section of the rubber faced bar upon which ⁶⁰ the plates rest.

Referring in detail to the drawings, upon a suitable standard 1 is mounted a shaft 2 carrying the fly wheel 3 to which is attached the operating handle 4. Said fly wheel carries a grooved wheel 5 for mechanical rotation of the shaft 2, when desired, by a suitable motor (not shown). Said shaft 2 is mounted in a bearing sleeve 6 formed on the standard 1. The inner end of said shaft 2 ⁶⁵ has a square portion 7 for connection with the tank 8. By means of a set screw 9, a collar 10 is fastened to the inner end of shaft 2 to keep said shaft from sliding out of place. Said squared end 7 of shaft 2 enters ⁷⁰ a socket member 11 having a square socket, said member 11 having a base plate 12 which is soldered or otherwise fastened to tank 8. To the opposite end of tank 8 is fastened a stud 13 by means of its base plate 14. The ⁷⁵ end portion 13a of said stud 13 is inserted within a supporting sleeve 15, said sleeve 15 being slidably mounted in a bearing sleeve 16, said sleeve 15 having a knob 17 to provide for manually sliding the same. A set ⁸⁰ screw 18 serves to secure the sleeve 15 in the adjusted position.

The purpose of the arrangement just described is to provide for removing the tank ⁸⁵ 8, and inserting in its place similarly designed larger or smaller tanks as desired. The tank 8 is mounted with the end walls thereof extending at an angle of substantially forty-five degrees with respect to the shafts 2 and 15, in order that the developing ⁹⁰ solution be more effectively thrown into contact with the picture plates 21 which are carried by a tray or holder or cage 22, shown in detail in Figs. 7, 8 and 9. Said holder 22 preferably consists of a pair of wire end ⁹⁵ loops or frames 23, a plate supporting member 24 upon which the lower ends of the plates 21 may rest, and a pair of corrugated guiding members or side pieces 25 uniting said frames 23, the corrugations of said ¹⁰⁰ members 25 being adapted to form runways or guides for the plates when the same are inserted. The supporting bar 24 is fastened at its ends to the bottoms of the frames 24. Said bar is provided with a rubber facing ¹⁰⁵ 110

24^a to guard the lower ends of the glass plates 21 from injury. A rubber tube or bar 26 may be placed between the tops of the plates 21 and the inner side of the lid 27 to 5 guard the upper ends of said plates from injury during the rotation of the tank.

In order to keep the developing solution at an even temperature, the tank 8 is formed with double walls 28 and 29 (see Fig. 4), 10 thus affording an air space 30 around said tank. Between the walls of the lid 27 is also preferably provided an air space 31. Said lid is clamped down by a bail 32 fastened to the tank by trunnions or ears 33. 15 Said bail carries a screw clamp 34 to clamp the lid 27 tightly in place, so as to permit the rotation of the tank without leakage of the developing solution therefrom.

In Fig. 5 is shown a modified form of 20 plate supporting cage 35 made of sheet metal and having end pieces 36 and side pieces 37. The side pieces 37 are provided with internally projecting runways or guides 38 to receive the picture plates 21.

25 In using either form of the cage, the plates are inserted in pairs, back to back. In the preferred form of the cage, shown in Figs. 7 and 8, only the corners of the plates engage the zig-zag guides; therefore, the 30 side portions of the plates cannot be scratched or marred by the cage. Picture plates may be developed very quickly by this appliance. The rhomboid form of tank gives the developing solution a back-and-35 forth movement while the tank is being rotated, thereby causing the developing solution to bathe the faces of the plates thoroughly and develop the pictures in about half the usual time. Owing to each side of 40 the tank being formed as a rhomboid, the open top of the tank, when brought uppermost, extends in a horizontal plane. The tank may be held in the upright position by forcing the sleeve 15 firmly against the base 45 portion of the stud 13 and then screwing down the set screw 18. After the cage 22 (or 35) has been filled with the plates 21

preparatory to inserting said cage and plates into the rotary tank 8, the entire handling of the plates during washing, placing in the "hypo" tank and hanging up to dry, may be done collectively while said plates remain in the cage, thus saving much time and also lessening the danger of injury to the plates incident to handling them separately. 50 55

I claim:

1. A tank, a shaft removably secured to one end of said tank and a longitudinally movable shaft at the other end of said tank 60 and axially in line with the first mentioned shaft, said tank being rotatably supported by and between said shafts.

2. A rotary tank, a closure for said tank, shafting whereon said tank is supported, 65 the end walls of said tank being at an oblique angle to said shafting and the side walls of said tank being substantially parallel to said shafting, and a rhomboidal cage adapted to fit within said tank to removably 70 secure photographic plates in said tank at an oblique angle to said shafting.

3. The combination, with a rotary tank, 75 of a plate-holding cage for insertion within and removal from said tank, said cage comprising a pair of loops or frames, one at each end of the cage; a plate-supporting member running along the mid-width of the cage from end to end thereof upon which the lower ends of the plates may rest, and a 80 pair of corrugated members uniting said frames, the corrugations of said corrugated members being adapted to form runways or guides for the opposite edges of the plates.

In testimony whereof I have hereunto 85 signed my name in the presence of two subscribing witnesses at Los Angeles, in the county of Los Angeles and State of California, this 24th day of March 1913.

WALTER RELLAND LAINE.
